GLOVE

Levi James Sabin, Youngstown, Ohio

Application September 9, 1935, Serial No. 39,685

5 Claims. (Cl. 2—161)

This invention relates to gloves.

The principal object is to provide a working man's glove and more particularly a glove to be worn by welders.

5 A further object is to provide a secondary back cover for the gloves.

A further object is to provide a heat breaker member for the protection of the workman's hands.

10 A further object is to provide an extended portion of the secondary back cover to provide protection for the side of the hand and the crotch formed by the index finger and thumb.

A further object is to provide inturned seams on 15 the secondary back member.

A still further object is to provide a secondary back cover having open ends.

With the foregoing and other objects in view which will appear as the description proceeds, the 20 invention resides in the combination and arrangement of parts and in the details of construction hereinafter described and claimed, it being understood that changes in the precise embodiment of the invention herein disclosed, can be made 25 within the scope of what is claimed, without departing from the spirit of the invention.

The invention is illustrated in the accompanying drawing, wherein:—

Figure 1 is a side view of a glove showing the 30 thumb side of the glove.

Figure 2 is a view of the glove showing the palm side of the glove.

Figure 3 is an enlarged cross section taken on line 3—3 of Figure 1.

35 Figure 4 is an enlarged cross section taken on line 4—4 of Figure 1.

Figure 5 is an enlarged cross section taken on line 5—5 of Figure 2.

40 Figure 6 is a detail view showing the pattern of the back of the glove and the heat breaker member.

Figure 7 is a detail view showing the pattern of the secondary back member.

By referring to the drawing it will be seen that 45 there is provided a welding glove having a cuff 1, a back member 2, and a palm member 12. This back member 2 is constructed with a heat breaker member 3. (See Figs. 4, 5, and 6.)

By referring to the drawing it will also be seen 50 that there is provided a secondary back cover 4. This secondary back cover is secured to the sides of the glove in a relatively loose manner and has each end open thus providing for the circulation of air as the workman opens and closes his hand.

55 By referring to Figures 3, 4, and 5 it will be seen

that the secondary cover 4 is secured to the sides of the glove by means of an inturned seam 5. By this particular construction the seam 5 is protected and at the same time tends to hold the secondary back member spaced apart from the back 5 2 of the glove.

By referring to Figure 7 it will be seen that a pattern of the secondary back member is shown. This pattern shows an extended side portion 6. By referring to Figure 1 it will be seen that this 10 extended side portion 6 extends out over the cuff seam 7 and the curved corner portion 8 protects the crotch 9 formed between the index finger 10 and the thumb 11.

This glove provides a protection for the hands 15 of a welder in performing his work. Welders commonly find the work so hot that they frequently dip their gloved hands in water to get relief from the intense heat. The important feature of this particular type of glove construction 20 is that it protects the hands so fully that it is unnecessary to continue this practice.

In the construction of these gloves it is desirable to use a good grade of leather, and the heat 25 breaker member 3 is preferably made of relatively heavy grade of fabric.

What I claim is:—

1. In a welder's glove comprising the usual back, palm, and cuff portions, a heat breaker comprising a piece of insulating material attached to the inside of said back portion and being substantially coextensive with said glove back, and a secondary back cover comprising a piece of material secured on the outer side of the back of the glove by inturned seams at both 30 sides with the intermediate material free of the glove back.

2. In a welder's glove comprising the usual back, palm, and cuff portions, a heat breaker comprising a piece of insulating material attached to the inside of said back portion and being substantially coextensive with said glove back, and a secondary back cover comprising a piece of material loosely secured on the outer side of the back of the glove by inturned seams at both sides 35 with the intermediate material free of the glove back, said secondary back cover extending from the wrist to the finger tips of said glove.

3. In a welder's glove comprising the usual back, palm, and cuff portions, a heat breaker comprising a piece of insulating material attached to the inside of said back portion and being substantially coextensive with said glove back, and a secondary back cover comprising a piece of material 50 loosely secured on the outer side of the back of 55

the glove by inturned seams at both sides with the intermediate material free of the glove back, an extended portion on secondary back cover extending over the seam on the cuff of said glove.

- 5 4. In a welder's glove comprising the usual back, palm, and cuff portions, a heat breaker comprising a piece of insulating material attached to the inside of said back portion and being substantially coextensive with said glove back, and a secondary back cover comprising a piece of material loosely secured on the outer side of the back of the glove by inturned seams at both sides with the intermediate material free of the glove back, an extended portion on secondary back cover extending over the seam on the cuff of said glove,
- 10 15 tending over the seam on the cuff of said glove, a curved corner portion on secondary back cover

extending over the crotch formed between the thumb and index finger.

- 5 5. In a leather glove comprising the usual back, palm, and cuff portions, a heat breaker comprising a piece of heavy fabric attached to the inside of said back portion and being substantially coextensive with said glove back, and a secondary back cover comprising a piece of material loosely secured on the outer side of the back of the glove by inturned seams at both sides with the intermediate material free of the glove back, a curved corner portion on secondary back cover extending over the crotch formed between the thumb and index finger.

LEVI JAMES SABIN. 15
